UNITED STATES PATENT OFFICE.

CHARLES J. RUNDQUIST, OF OPHEIM, ILLINOIS.

FOOT-POWER HAMMER.

SPECIFICATION forming part of Letters Patent No. 379,818, dated March 20, 1888.

Application filed January 3, 1888. Serial No. 259,581. (No model.)

To all whom it may concern:

Be it known that I, CHARLES J. RUNDQUIST, a citizen of the United States, residing at Opheim, in the county of Henry and State of Illinois, have invented certain new and useful Improvements in Foot-Power Hammers, of which the following is a specification.

This invention relates to that class of hammers which are operated by foot-power, and 10 which are adapted, mainly, for the use of blacksmiths; and the invention consists in an improved frame for supporting the working parts, in improved means for adjusting the hammer vertically and adjusting the other 15 parts to correspond therewith, in improved means for adjusting the hammer toward and from the anvil, in improved means for actuating the hammer, in improved means of increasing and diminishing the force of the blow 20 of the hammer, and in combinations and constructions hereinafter described and claimed.

In the accompanying drawings, which illustrate a foot-power hammer embodying my invention, Figure 1 is a side elevation; Fig. 2, a 25 sectional elevation of the parts shown at Fig. 3 and in the line 2 2 of said figure, showing the lower end of the screw-rods used for adjusting the height of the hammer-carrying frame or carriage; Fig. 3, a top plan of the adjustable 30 hammer-carrying carriage, a sectional plan of the frame-posts, and the screw-rods for adjusting the hammer-carrying carriage, and part of the hammer-handle; Fig. 4, a detail, a top plan of the bumper and its carrying-bar, and horizontal 35 sectional plan of the frame-bars supporting it and plan of the attaching-hooks; Fig. 5, a sectional elevation of part of the device in the line 5 5 in Fig. 6; Fig. 6, an elevation, partly in section, in the line 6 6 in Fig. 1, except that 40 the hammer-handle is shown broken away back of the line 1 1.

The main frame is formed of base or foundation bars A A, to which are bolted the upright frame-bars a a' a'. The bars a a are formed 45 of a single bar bent in such manner that its middle portion forms a horizontal base part, a², which is bolted to the bars A, and its end portions form the upright frame-bars a. The bars a' are formed and fixed similarly to the bars 50 a, and the bars a a' are stayed and braced by

transverse frame-bars a³ a⁴ and crossed braces a⁵, which crossed braces are bolted to the bars a a' and to the bars A, as shown. A bar, a⁶, bolted to each side of the frame, extends to and is bolted to the anvil-block B, which thus 55 forms a part of the main frame. This structure will form a simple, strong, solid, substantial iron frame, and such as is very desirable and useful in hammers of this class.

C are bars, one at each side of the frame, 60 and constitute parts of the hammer-carriage, a top plan of which is shown at Fig. 3. The bars C are adjustable in height by means of screw-rods c', one screw-rod to each bar C. The rods c' each pass through a loop or eye, 65 c², on the top frame-brace, a³, which is above and adjacent to each, and the screw-threaded portion of each rod c' passes through screw-threaded holes in lugs c³, which project from the bars C. The rods c' are not screw-threaded 70 where they pass through the eyes c², and have each a fixed collar, c⁴, above and below the eye c². The upper ends, c⁵, of the rods c' are square in their cross-sections, so that by means of a wrench placed thereon they may 75 be turned to raise and lower the bars C in an evident manner. The bars C are held, after the adjustment last described, by means of clamps c⁶, one of which is seated over each frame-bar a a', and the ends of which pass 80 through the adjacent part of a bar, C, and are tightened on the bars a a' by nuts c⁷, to fix the bars C firmly at any desired height to which they may be adjusted by the screw-rods c'. Prior to adjusting the bars C the nuts c⁷ are 85 turned to loosen the grasp of the clamps c⁶ on the bars a a'.

D is a rock-shaft supported in suitable bearings, d, which are fixed to the bars C.

E is a clamp-plate, its ends bent downwardly, 90 and provided with elongated holes, through which the rock-shaft D passes. Eyebolts F encircle the shaft D, and their stem ends pass through the clamp-plate E and through another clamp-plate, E', located above the plate E, and 95 are provided with nuts f'. The clamp-plate E' is bent to form a seat, e, for the handle g of the hammer G.

H H' are arms or levers, each having a slot, h. The arms or levers H H' are located be- 100

tween the clamp E and rock-shaft D, and project forwardly therefrom, for purposes herein-after described. The eyebolts F pass through the slots h. When the nuts f are loosened on the eyebolts, the hammer-handle g may be moved lengthwise of itself to adjust it in its seat e, and the levers H H' may also be ad-justed lengthwise of themselves, and the handle g and levers H H' are both securely held after adjustment by tightening the nuts f on the eyebolts F. The arm or lever H' is hinged in the upper slotted end of a link-rod, I, by a pivot-bolt, i.

The bolt i may be seated in either of a series of holes, i', in the link-rod I. The lower end of the rod I is hinged to the end of a spring, J, which is secured at its other end to a standard, j, and exerts an upwardly-acting force on the lever H', the degree of which force is regu-lated or adjusted by adjusting the bolt i in the series of holes i' in the link I, and further ad-justed by adjusting the lever H' lengthwise on the rock-shaft D, as hereinbefore described. When the bars C are adjusted to raise or lower the rock-shaft D, the lever H' can be adjusted, or the link I, to correspond, by the means last described; and by adjusting the lever H' lengthwise of itself, as hereinbefore described, the force with which the spring J acts thereon 30 may be controlled to a limited extent.

K is a lever hinged at one end to a clip-bolt, k, which is secured to one of the frame-bars a. A link-rod, L, connects the lever K, near its mid-length portion, with the end of the lever H. The link-rod L is forked where it receives the lever H, and is provided with a series of holes, l, for a pivot-bolt, l', which hinges it to the lever H. When the bars C are adjusted in higher or lower positions, as hereinbefore described, the holes l are used to correspondingly adjust the lever H on the link L, and by adjusting the lever H lengthwise of itself, as herein described, the force exerted upon the hammer by the operator's foot, as 45 hereinafter described, may be increased or diminished.

M is a stirrup adjustable on and lengthwise of one of the bars a⁶, and is held after adjust-ment by a bolt, m. A stud or pin, m', projects from the stirrup M and forms a pin-pivot or journal for a lever, N. The lever N is hinged at one end to the power end of the lever K by a link-rod, n, and at its other end to a link, P, which is also hinged to the end of the pedal-55 lever Q, the pedal end of which is convenient to the anvil-block B, and the central part of which is hinged or journaled to a standard, q, which projects from the anvil-block. The lever N has a series of holes, n, for the pin m', and when the stirrup M is adjusted lengthwise of the bar a⁶ the pin m' may be inserted in a hole, n', adjacent, and thus the fulcrum of the lever N be changed lengthwise of said lever to increase or diminish the force which may be 60 given to the blow of the hammer by the op-erator pressing downwardly with his foot on

the power end of the lever Q. The spring J restores the parts to their normal positions after each blow of the hammer.

Anvils B', of any construction suitable to the 70 work to be done, may be used on the block B, and the hammer may be adjusted, as herein-before described, toward or from the anvil, as may be required in different kinds of work.

Operating the hammer with his foot, the 75 operator may not only give a harder blow, but his hands are left free to manipulate the iron under the hammer. To arrest the up-ward movement of the hammer at the proper time, I provide a rubber bumper-block, R, 80 seated above the hammer-handle in a socket, r, which projects from a bar, r', which is se-cured to the bars a a by hook-bolts r², by means of which the bar r' and the bumper it carries may be adjusted, in an evident manner, in 85 higher or lower planes, to suit the vertical ad-justments of the hammer carriage.

If preferred, the lever K may be connected with and operated by any suitable engine or other motor.

What I claim as new is—

1. In a foot-power-hammer frame, in com-bination, base-bars A, upright frame-bars a a', having connecting portions a² bolted to the base A, ties a³ a⁴, crossed braces a⁵, bars a⁶, and 95 anvil-block B, substantially as and for the pur-pose specified.

2. In a power-hammer, in combination with frame-bars a a', bars C, having a rock-shaft, D, journaled thereto, the hammer-handle mounted 100 on the shaft D, the bar a⁸, having an eye, c², screw-rod c', and lugs c³, projecting from the bars C, whereby the hammer-carriage may be adjusted vertically, substantially as described.

3. In a power-hammer, in combination with 105 frame-bars a a', bars C, having a rock-shaft, D, journaled thereto, clamps c⁶, the hammer-han-dle mounted on the shaft D, the bar a⁸, having an eye, c², screw-rod c', and lugs c³, projecting 110 from the bars C, whereby the hammer-carriage may be adjusted and secured after adjustment vertically, substantially as described.

4. In a power-hammer, in combination with frame-bars a a', bars C, having a rock-shaft, D, journaled thereto, the hammer-handle mounted 115 on the shaft D, the bar a⁸, having an eye, c², screw-rod c', having collars c⁴, and lugs c³, pro-jecting from the bars C, whereby the hammer-carriage may be adjusted vertically, substan-tially as described.

5. In combination with the rock-shaft D, carried by vertically-adjustable bars, a clamp-plate, E, and eyebolts F, the slotted and ad-justable lever H', link I, having series of holes i', and spring J, whereby the tension of the 125 spring may be controlled to suit vertical ad-justments of the hammer-carriage, substan-tially as described.

6. In combination with a rock-shaft, D, carried by vertically-adjustable bars, a clamp-plate, E, and eyebolts F, the slotted and ad-justable lever H', and a link, L, having series 130

of holes l , connecting it with suitable actuating mechanism, whereby the force of the hammer-blow may be regulated and hammer-carriage be adjusted vertically without disturbing 5 the actuating mechanism, substantially as described.

7. In combination with a rock-shaft, D, clamps E and E', and eyebolts F, the hammer G, the handle of which is adjustable between 10 the bolts E and E', substantially as described.

8. In combination, frame-bars a a' , adjustable plates C, rock-shaft D, clamp-plates E E', slotted levers H H', and a hammer and handle, 15 G g, substantially as and for the purpose specified.

9. In combination, frame-bars a a' , adjustable plates C, rock-shaft D, clamp-plates E E', slotted levers H H', and a hammer and handle, G g, a spring, J, connected with the lever H', 20 and suitable actuating mechanism connected with the lever H, substantially as and for the purpose specified.

10. In combination with a rock-shaft, D, and clamp-plates held thereto by eyebolts 25 F, the adjustable levers H H', and hammer

and handle G g, substantially as and for the purpose specified.

11. In combination with the rock-shaft D and hammer mounted thereon, the lever H, link L, levers K, N, and Q, and links P n, substantially as and for the purpose specified. 30

12. In a foot-power hammer, in combination with the levers K, N, Q, and H and their connecting links, and the hammer and rock-shaft D, the adjustable fulcrum m' for the lever N, substantially as and for the purpose specified. 35

13. In combination with the adjustable bars C, the rock-shaft D, the hammer and its actuating mechanism, the bumper R, fixed to a bar, 40 r' , and the hook-bolts r^2 , for adjusting the bumper vertically on the bars a to suit vertical adjustments of the hammer-carriage, substantially as described.

In testimony whereof I affix my signature in presence of two witnesses.

CHARLES J. RUNDQUIST.
